UNITED STATES PATENT OFFICE.

LEO DI REBAYLIO, OF BLOOMFIELD, NEW JERSEY.

MULTICOLOR PENCIL CASE.

Application filed February 4, 1926. Serial No. 85,947.

This invention relates to multi-color pencil cases, and belongs to that class or type of writing or marking devices that are intended to permit the user a selection of the 5 color of the pencil, chalk or crayon for any purpose.

The object of this invention is the production of a pencil case or container of the character stated possessing parts of special construction and operation whereby it is believed a particularly strong, convenient and inexpensive article of manufacture is obtained, and which is of good appearance externally.

15 In the accompanying drawings, illustrating the preferred forms and arrangement of the various parts of this invention, the scale of drawing has been intentionally augmented to enable the smaller parts and their locations to be plainly seen. It is intended that the invention shall be made up in sizes convenient for carrying in the pocket in like manner with the ordinary fountain pen.

Fig. 1 of the drawings is a side view partly in section vertically and lengthwise of the casing. Fig. 2 is a top plan view. Fig. 3 is a fragmentary sectional view of one of the pencil carrying slides located in a groove of the revoluble pencil support. Fig. 4 is a 20 cross-section on the indirect broken line 4—4 of Fig. 1.

Throughout the drawings and description the same number is used to refer to the same part.

35 Considering the drawings, the casing 1, which may be made of hard rubber or any chosen metal, has an issue terminal 2 for the pencil, a slot 3 extending lengthwise of the casing in the direction of the terminal, and a transverse slot 4 terminating the slot 3 at 40 about the middle of the length of the casing.

45 Finger pieces or small knobs 5 and 5^a are made of such size as to pass through the transverse slot 4. Each finger piece has a stem or connection 6, usually formed with a projecting end 7 and of spring wire, that forms the attachment to the slide 8 that carries the pencil 9, as best shown in Fig. 3.

50 Each pencil and its carrier slide travels a groove 10 formed lengthwise in a pencil support 11, which is a cylindrical body. Each groove 10, of which there may be any desired number, can be brought to register with the issue orifice 12 in the terminal 2 of 55 the casing. It will be noted that the issue terminal and orifice are located on one side

of the central longitudinal axis of the casing, and that the cylindrical member 11 is arranged against the side of the casing having the slot 3.

60 Reference number 13 is a stop cup located within the casing and provided with a bearing 14 for the inner end of the cylindrical member 11, the other end of which is revolvable in contact with the tapering end of the 65 casing at which the terminal 2 is placed. That is to say, the cylinder 11 may be revolved in bearing 14 and in the tapering end portion of the casing in which it is fitted.

Again considering Fig. 3, it will be noted 70 that the end 7 of the connection 6 of the finger piece 5 touches the stop 13. This contact limits the inward movement of the slide and brings the finger pieces in proper register with the transverse slot 4 in the casing. 75

The operation so far as projecting or withdrawing the pencil 9 is concerned is the same as usual in such cases. The connection 6 of the finger piece 5 is made to travel the slot 3, and the point of the pencil may be exposed 80 as far as need be. The end 7 of the connection 6 presses upon the bottom of the groove 10, and thus holds the slide against the inside of the casing, and the pencil in position.

It will be noted from Fig. 4 that if the finger piece 5 be moved towards the left hand 85 its engagement with the slide in the groove 10 will revolve the cylinder support 11, and the second finger piece 5^a will pass outwardly through the transverse slot 4 in the casing, while at the same time the finger piece 5 will pass inwardly through the same slot 90 into the casing. As drawn, although not essentially so, the movement outwardly of one finger piece is in the opposite direction to the 95 movement outwardly of the second finger piece.

It is thought that various modifications may be readily made within the purview of this invention, and the claims are not intended to be confined to the precise forms and dispositions of the parts illustrated.

Having now described this invention and explained the mode of its operation, what I claim is:—

1. A multi-color pencil case, comprising an external casing tapering to an issue terminal arranged at one side of the central longitudinal axis of the casing, a cylindrical pencil support having spaced grooves formed lengthwise therein, means for holding the said cylindrical support revolvable within the 110

casing, pencil carrying slides movable in the said grooves, the said casing having a slot extending lengthwise therein towards the said terminal, a transverse slot in the casing 5 terminating the said lengthwise slot, finger pieces having connections attached to the said slides and constructed to be moved in the said lengthwise slot of the casing and whereby the said cylindrical support may 10 be revolved, and the said finger pieces constructed to be turned outwardly through the said transverse slot into an operative position and inwardly through the said slot into an inoperative position.

15 2. A multi-color pencil case, comprising a casing, a longitudinally grooved support for the pencils revoluble in the casing, the pencils being movable lengthwise in the grooved support, the said casing having a 20 transverse slot and a longitudinal slot opening into the transverse slot, finger pieces movable in the said transverse slot and acting upon the said support to partly rotate the same, each finger piece being constructed 25 to travel the said longitudinal slot in the casing, and means for connecting the finger piece and a pencil whereby the pencil may be moved out through the end of the casing and withdrawn.

30 3. A multi-color pencil case, comprising a casing, a revoluble support in the casing, the pencils being carried by said support and movable lengthwise thereon, the said casing having a transverse slot and a longitudinal 35 slot opening into the transverse slot, finger pieces movable in the said transverse slot and acting upon the said support to partly rotate the same, movable means carried by the support for connecting the finger pieces and pencils, each finger piece having a termination 40 movable through the transverse slot into the casing on rotating the said support in one direction, and movable out through said slot on a contrary rotation of the support, and each finger piece being constructed to travel the said longitudinal slot in the casing whereby a pencil may be moved out through the end of the casing and withdrawn.

45 4. A multi-color pencil case, comprising

an external casing tapering to an issue terminal arranged at one side of the central longitudinal axis of the casing, a cylindrical and revoluble pencil support having spaced grooves formed lengthwise therein, the said cylindrical support having one end revolvable in contact with the tapering end of the casing, a bearing located within the casing for the other end of the said support, pencils in the said grooves, pencil carrying 50 slides movable in the said grooves, the said casing having a slot extending lengthwise therein towards the said terminal and a transverse slot in communication with the said lengthwise slot, finger pieces having 55 connections with the said slides constructed to move along the said lengthwise slot of the casing, and the said finger pieces being arranged to revolve the said support and to be moved outwardly through said transverse 60 slot into an operative position and inwardly through the said slot into an inoperative position.

5. A multi-color pencil case, comprising a casing, a revoluble support in the casing, the 70 pencils being carried by said support and movable lengthwise thereon, the said casing having a transverse slot and a longitudinal slot opening into the transverse slot, finger 75 pieces movable in the said transverse slot and acting upon the support to partly rotate the same, movable means carried by the support for connecting the finger pieces and pencils, each finger piece having a termination 80 movable through the transverse slot into the casing on rotating the said support in one direction, and movable out through said slot on a contrary rotation of the support, and each finger piece being constructed to travel the said longitudinal slot in the casing 85 whereby a pencil may be moved out through the end of the casing and withdrawn.

In testimony whereof I affix my signature.

LEO DI REBAYLIO.
